CLOTH REWINDER AND MEASURER

Filed Nov. 21, 1933

UNITED STATES PATENT OFFICE

2,010,891

CLOTH REWINDER AND MEASURER

Paul E. Raymond, Greenwich, Conn.

Application November 21, 1933, Serial No. 698,980

2 Claims. (Cl. 33—129)

This invention relates to a machine or device which may be either operated by hand or by power for the rewinding and measuring of fabrics which are in the form of bolts of cloth or the like, and the invention relates more particularly to a device for rewinding, for sale, small quantities from a stock bolt of cloth.

One of the objects of the invention, is to provide a device for rewinding and measuring the length of textile fabrics, and in which a measuring roller is employed, and means for retaining the fabric in rolling contact therewith to insure an even and accurate measurement without any slipping or creeping of the fabric with respect to the measuring roller.

Another object of the invention is to provide a device provided with means for rewinding the fabric in the same manner and shape as that of the original stock bolt.

A further object of the invention being to provide means whereby fabric of different widths may be rewound and measured, and the entire length of the piece measured.

Another object being to provide means whereby the core-board that the bolt of fabric comes wound upon from the factory may be removed and replaced with one of the mandrels of the machine for the purpose of rewinding, or the fabric may be rewound upon the usual core-board if so desired.

With these and other objects in view, my invention consists in certain novel construction and combination of parts as will hereinafter be fully described and claimed, and further illustrated in the accompanying drawing which forms a part hereof and in which like figures of reference refer to corresponding parts in all of the views, and it is understood that slight changes may be made without departing from the spirit of the invention.

In the drawing:

Figure 1 is a top plan view of the device showing a bolt of cloth in position to be rewound and measured.

Figure 2 is a side elevation of the same.

Figure 3 is a top plan view of one of the mandrels, showing means for holding core boards of varying lengths thereon to wind the cloth upon.

Figure 4 shows an edge view of the same, partly in section to illustrate the method of holding the core boards.

Figure 5 is a cross sectional view of Figure 3.

Referring to the drawing:

The device is mounted on a base-plate 10 as here shown, but the several parts or supports

may be combined with and made integral with a suitable base.

A pair of supporting brackets 11 are secured to the base 10 by the screws 13, and the upper ends of these supports 11 are formed with the U-shaped bearings 12 which are aligned with each other and in which is supported in a freely rotatable manner the trunnions 9 which are formed on each end of the mandrel 14, and which are only slightly larger in diameter than the thickness 10 of the mandrel.

Said mandrel 14 is formed of suitable material such as metal, and is rectangular in cross section and provided with a central slot 15 and a series of openings 16 for the purpose of reducing 15 its weight; while one end adjacent the trunnion 9 is formed with a flange against which the bolt of cloth may be abutted to act as a guide.

Near the other end of the base plate 10, is mounted a similar pair of supports 17 by the 20 screws 13, and they are also formed with U-shaped bearings 18 at their upper ends, within which are rotatably mounted the trunnions 19 of the mandrel 20; one of said trunnions 19 being extended and having secured thereon a hand crank 21, by which the mandrel is rotated, but it is understood that for this crank, a pulley or other power operating means may be substituted.

The mandrel 20 is similar in design to the mandrel 14 as shown in Figures 1 and 2, but the special mandrel as shown in Figures 3 and 4, may be substituted.

The tension and measuring device, comprises a pair of bearing blocks 22 which are formed with the aligned bearings 23, and secured to the base plate 10 by the screws 13, and within said bearings 23 is mounted in a freely rotatable manner a shaft 24 upon which is mounted a measuring roller 25 of some suitable material having a mat surface to prevent the slipping of the cloth; this measuring roller 25 having a periphery equal to a predetermined measurement such as one foot, so that each revolution will measure one foot of the cloth; the end of the shaft 24 being attached to a standard counter 26 mounted on one of the 45 bearing blocks 22; this counter registering the feet and inches or parts of a yard or foot as the case may be.

For exerting the proper tension upon the cloth as it is being wound and to keep it in contact 50 with the measuring roller 25, there is provided the two arms 27 which are mounted on the ends of a rod 28 which is journaled in the bearing blocks 22, and the outer ends of these arms 27 have secured therein a shaft 29 upon which is 55

mounted a roller 30 which is in contact with the cloth; the swing of these arms 21 being limited by the stop pins 31.

By referring to Figure 2, it will be seen that 5 the stock bolt of cloth 32 having had its core removed and replaced by the mandrel 14 freely turning in the bearings 12, the cloth is threaded around an idler roller 33 mounted in bearings 34 in the standards 11; then to and around the 10 measuring roller 25, around the roller 30 and from there to the mandrel 20 upon which it is wound by the rotation of the same as actuated by the hand lever.

For rewinding the cloth upon cores in place of 15 upon the mandrel alone, the mandrel 35 as shown in Figures 3, 4 and 5, is provided, and this is similar to the regular mandrel with the exception that it is provided with two removable and 20 adjustable end clamps for holding a core board 25 upon one side thereon; one of said clamps 42 being placed adjacent the flange 37 and the other being mounted in a sliding manner in the slot 15, and comprising a base 38 having a tongue 39 extending through said slot 15 and secured by a 25 plate 49 in contact with the lower face of the mandrel 35; while mounted upon said base 38 by the ears 46 and rod 41, is a finger clip 42 which may be rocked on the base 38 against the spring 43 which holds the same in gripping relation with 30 the core board 44.

To remove the bolt of cloth after the same has been rewound upon the core board 44; the outer 35 clamp is removed from the mandrel 35, the core board 44 is released from the other clip or clamp, and the core board 44 with the cloth wound thereon is slid off of the mandrel 35.

The outer clamp 38 is so constructed that it 40 may be removed from the mandrel to allow the core-board 44 and cloth to be slid off of the mandrel; this removal of the clamp 38 being effected by the removal of the bottom plate 40 or by any suitable means.

It is to be noted that due to the fact that the 45 cloth is not wound tightly on either the mandrel or the combined mandrel and core board and

owing to the natural stretch of the material it is easy to slip the bolt of cloth over the trunnion 19 and still have it tight enough to hold on the core-board and any looseness thereon in no way effecting the same.

Having thus described my invention, what I claim as new and desire to secure by Letters Patent, is:

1. In a device for measuring and rewinding fabric, the combination with a base having two 10 pairs of mandrel supporting brackets mounted thereon in spaced relation with each other and each pair formed with aligned bearings, a pair of bearing blocks mounted on said base between said pairs of brackets and formed with aligned 15 bearings, a measuring contact roller freely rotatably mounted in said blocks, a shaft mounted in said blocks in parallel relation with the contact roller, a pair of arms secured to the ends of said shaft, a tension roller carried by said arms, stops 20 formed on said blocks for limiting the swing of said arms, a guide roller mounted in one pair of brackets adjacent the lower ends thereof, and a pair of fabric receiving mandrels demountably carried by said brackets and being rectangular in 25 cross section.

2. In a machine for measuring and rewinding fabric, the combination with a base having two 30 pairs of supporting brackets mounted thereon and formed with bearings, of a pair of bearing 35 blocks mounted on said base between said pairs of brackets and formed with aligned bearings therein, a measuring roller mounted in said bearings and means for registering the revolutions thereof, a pair of swinging arms pivoted to said bearing blocks, a tension roller rotatably mounted in said arms and parallel with the measuring roller, means attached to said blocks for limiting the swing of said arms, a guide roller mounted in one pair of brackets, demountable mandrels 40 mounted in the bearing in said brackets, rectangular in cross section, adjustable clamps mounted thereon for holding a core-board thereon.
